CLAIM

The ornamental design for an eye beauty instrument, as shown and described.

DESCRIPTION

FIG. 1 is a front, left and top perspective view of an eye beauty instrument, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right-side elevation view thereof.

FIG. 7 is a top plan view thereof.

FIG. 8 is a bottom plan view thereof.

FIG. 9 is a partial enlarged view of an area labeled 9 in FIG. 1 comprising a part of a handle.

FIG. 10 is a partial enlarged view of an area labeled 10 in FIG. 2 comprising a part of a head; and,

FIG. 11 is another front, left and top perspective view of the eye beauty instrument shown separately to show aspects of the design that are not visible when combined.

The broken lines shown in the drawings are included for the purpose of illustrating portions of the eye beauty instrument that form no part of the claimed design.

The dash-dot broken lines shown in FIGS. 1, 2, 9 and 10 are for the purpose of showing enlarged areas, which form no part of the claimed design.
